UNITED STATES PATENT OFFICE.

EDWARD SCHUMER, JOHN SCHUMER, RUBY C. SCHUMER, AND EDWARD H. WUBBOLDING, OF CINCINNATI, OHIO, ASSIGNEES TO SCHUMER BROTHERS, A FIRM COMPOSED OF EDWARD SCHUMER, JOHN SCHUMER, AND RUBY SCHUMER, OF CINCINNATI, OHIO.

SETTING FOR PRECIOUS STONES.

1,322,062.

Specification of Letters Patent. Patented Nov. 18, 1919.

Application filed August 5, 1919. Serial No. 315,534.

To all whom it may concern:

Be it known that we, EDWARD SCHUMER, JOHN SCHUMER, RUBY C. SCHUMER, and EDWARD H. WUBBOLDING, all citizens of the 5 United States of America, and residents of Cincinnati, in the county of Hamilton and State of Ohio, have invented a new and useful Improvement in Settings for Precious Stones, of which the following is a specification.

Our invention relates to means for setting precious stones, of comparatively small size, in an article of jewelry so that they will resemble a single large stone.

15 Our invention relates particularly to a means of providing something to resemble the facets of a diamond below the girdle. Heretofore, the means for giving the appearance to the cluster, of the aforesaid facets, 20 has been a frame which was secured either to the plate in which the diamonds were set or which was secured to the setting prongs of the article of jewelry.

One of the objections to the former 25 mounting means is that the frame work interferes with the removal of the surplus cement which was used in setting the diamonds in the plate. One of the objections to the latter is that it is difficult to secure 30 each wire to the interior of the setting prongs.

It is the object of our invention to provide a means for setting a cluster of precious stones which will not interfere with the removal of surplus cement and which may be 35 manufactured economically.

This and other objects are attained by the means described in the specification and illustrated in the accompanying drawings, 40 in which:—

Figure 1, is a front view of a ring provided with a setting embodying our invention.

Fig. 2, is a side elevation thereof.

45 Figs. 3 and 4, are respectively a front and sectional view of the cluster plate.

Figs. 5 and 6, are similar views of the frame.

Fig. 7, is a detail view partly in section and partly in side elevation and upon an 50 enlarged scale showing the relative positions of the plate, the frame and the setting prongs.

We have illustrated our invention as applied to a ring A having setting prongs *a* 55 of the Tiffany type. Plate B is of the usual circular slightly convex shape, and has in it the usual set of holes *b* for receiving and holding the stones in juxtaposition so as to give the appearance of a single stone. The 60 frame consists of a ring D, and a series of wires. Each of the wires *d*, *d'*, *d''*, is secured at its ends to diametrically opposite points of ring D and intermediate its ends is bent downward and at its point of intersection with the other wires is soldered 65 thereto.

In manufacturing a cluster embodying our invention, after the gems have been placed in the plate B, it is cleaned upon each side, 70 a process which is readily performed since unobstructed access may be had to each side of the plate. Then the frame is seated in the setting prongs, the plate B bearing its cluster of stones is then seated on the frame, 75 and the ends of the prongs are bent inward over the plate.

Having thus described our invention, what we claim is:—

A cluster setting comprising a perforated 80 plate adapted to receive and hold precious stones and a frame comprising a separate ring and a series of wires secured to the under side of the ring and extending diametrically across the ring.

85 In testimony whereof we have hereunto subscribed our names this 4th day of August, 1919.

EDWARD SCHUMER.

JOHN SCHUMER.

RUBY C. SCHUMER.

EDWARD H. WUBBOLDING.
